UNITED STATES PATENT OFFICE.

JOSEPH H. SPRINGER, OF PHILADELPHIA, PENNSYLVANIA, ASSIGNOR TO HIMSELF AND MILTON FOREMAN, OF SAME PLACE.

IMPROVEMENT IN STEAM-BOILERS.

Specification forming part of Letters Patent No. 41,665, dated February 16, 1864.

To all whom it may concern:

Be it known that I, JOSEPH H. SPRINGER, of Philadelphia, Pennsylvania, have invented an Improvement in Steam-Boilers; and I do hereby declare the following to be a full, clear, and exact description of the same, reference being had to the accompanying drawings, and to the letters of reference marked thereon.

My invention consists of any desired number of tubes, each of which has an internal or air tube and a series of openings, the said tubes being bent and arranged in the boiler as described hereinafter, so as to insure the ignition of the unconsumed products of combustion without injury to the tubes.

In order to enable others skilled in the art to make and apply my invention, I will now proceed to describe its construction and operation.

On reference to the accompanying drawings, which form a part of this specification, Figure 1 is a vertical section of sufficient of a locomotive-boiler to illustrate my invention; Fig. 2, a transverse vertical section on the line 1 2, Fig. 1, and Fig. 3 an enlarged sectional view of one the air-tubes.

Similar letters refer to similar parts throughout the several views.

A represents the fire-box of a locomotive-boiler; B, the combustion-chamber; a, the front tube-plate, and C part of the body of the boiler, all of which parts are similar in construction to those of locomotive-boilers in general use. In the combustion-chamber I arrange the two air-tubes D and D', which are bent to the form, or nearly to the form, best observed on reference to Fig 2, the upper end of the tube D being secured to the side d of the combustion-chamber, near the upper corner of the same, and the lower end of the tube to the side d', near the lower corner of the said chamber. The tube D' is arranged in the reverse position, its upper end being secured to the side d' and lower end to the side d of the combustion-chamber. Within each tube is another tube, E, bent to the same form as the outer tube, and between the two tubes is an annular space, f, best observed on reference to Fig. 3.

Both of the tubes D and D' are so secured to the sides of the combustion-chamber that the space between the inner and outer tubes shall communicate both above

and below with the water-spaces between the combustion-chamber and the outer shell of the boiler, as seen in Fig. 2. Each inner tube is closed at the upper end, the lower end passing through the water-space—one tube on one side and the other tube on the other side of the boiler—and both tubes communicating with the external atmosphere.

In each of the tubes D and D', and at suitable intervals, are openings i, (see Fig. 3,) forming communications between the interior of the inner tubes, E, and combustion-chamber.

It will be observed on reference to Fig. 1 that the two tubes D and D' are arranged one a little in advance of the other. As many additional tubes as desired, arranged in a similar manner in respect to each other and to the combustion-chamber, may, however, be introduced into the latter.

As the products of combustion pass from the fire-box into the combustion-chamber, they are met by jets of air passing through the openings i of the tubes D and D', by which jets the unconsumed gases are ignited and pass off in the form of flames from the combustion-chamber into the usual tubes. A free and uninterrupted circulation of water is maintained through the space between the inner and outer tubes; hence the inner tube or air-tube is not only efficiently protected against the action of the fire, but the air is heated prior to passing off in jets through the openings i.

It is important that the tubes should be bent to the form shown in the drawings, or to some other form that will permit the said tubes to yield to a limited extent and accommodate themselves to any unequal expansion and contraction which may take place.

I claim as my invention and desire to secure by Letters Patent—

The tubes D, internal tubes, E, and air-openings i, when the said tubes are formed and arranged within the boiler as and for the purpose described.

In testimony whereof I have signed my name to this specification in the presence of two subscribing witnesses.

JOSEPH H. SPRINGER.
